UNITED STATES PATENT OFFICE.

WARNER R. BUXTON, OF LONGMEADOW, MASSACHUSETTS, ASSIGNOR TO BUXTON, INCORPORATED, OF SPRINGFIELD, MASSACHUSETTS, A CORPORATION OF MASSACHUSETTS.

KEY CASE.

1,423,909.

Specification of Letters Patent. Patented July 25, 1922.

Application filed May 20, 1920. Serial No. 382,866.

To all whom it may concern:

Be it known that I, WARNER R. BUXTON, citizen of the United States, residing at Longmeadow, in the county of Hampden 5 and State of Massachusetts, have invented new and useful Improvements in Key Cases, of which the following is a specification.

This invention relates to cases for keys and the like and, more particularly, to improvements in key cases of the type disclosed in my prior Patent No. 1,261,692 granted April 2, 1918.

The key case of my prior patent utilized, as key supporting devices, snap hooks of the usual form. Such hooks satisfactorily perform their function when made of good steel and properly tempered but, even with good steel, unless great care is taken in their manufacture (which means considerably increased costs) it is difficult to obtain hooks which will not, after continued use, acquire a certain degree of "set." That is, eventually, the abutting ends, which form the "break" in the loop, will not exactly meet, leaving a projection on the interior of the loop upon which the key may catch. Under some conditions, this results in the key working its way out of the loop directly between the ends, which should be in close engagement to prevent such action. The difficulties with hooks of the ordinary type is accentuated when the key, while still retained in the hook of the key case, is turned in the lock. The turning of the key results in side strains 25 on the loop, which sometimes causes the mating ends of the loop to be bent out of alignment, thereby permitting the escape of the key. Even when the snap hook is of proper temper, the turning of the key causes a strain on the lower part of the "broken" wall 40 of the loop and tends to deflect it out of line with the upper part of such wall and thereby permits the escape of the key. Thus, snap hooks of the ordinary type do not work out 45 as satisfactorily in a key case, of the general type disclosed, as they do in other fields of general service, where the special conditions, incident to the use of the key case, are not encountered.

The object of this invention is to improve the key supporting devices in a key case of the general type disclosed in my prior patent.

More particularly, it is an object of the invention to provide, in a key case of this general type, snap hooks which have key receiv-

ing loops of the usual shape but which are characterized by having the "break" or entrance and exit portion, at the apex of the loop.

Another object is to provide, in a device of the class described, hooks having loops of usual shape but with the "break" at the apex, wherein one end of the member forming the hook is adapted for a pivotal connection and the other end of the member projects outwardly from the apex to prevent the key, when swung backwardly from its normal pendant position in the loop, from lying flat and in line with the apex of the loop, thereby rendering accidental dislodgment of the key 70 from the loop more difficult.

Other objects and advantages will appear in the following description and in the illustrative embodiment of the invention in the accompanying drawings in which:

Fig. 1 is an elevational view of the key case with the flaps opened;

Fig. 2 is a similar view with the flaps closed;

Fig. 3 is an enlarged fragmentary cross 80 sectional view thereof, showing the improved hook;

Fig. 4 is a view somewhat similar to Fig. 3 and illustrative of the use of the projections on the hooks;

Fig. 5 is a fragmentary perspective view 85 of the pivot frame;

Fig. 6 is a fragmentary sectional view thereof; and

Fig. 7 is a view similar to Fig. 5, showing 90 a modification in the hook.

Referring to these drawings; the case proper comprises a strip of flexible material, such as leather or the like, which is foldable along the dotted lines 10, shown in Fig. 1, to form a back 11 and two flaps 12, which may be folded in overlapping relation over the back 11, as indicated in Fig. 2, and removably secured together in any suitable manner, as by the male and female snap 100 fasteners 13 and 14 respectively.

Secured to the back 11, preferably adjacent the top thereof, is a frame 15 which may advantageously be struck up from flat thin metal. The upper edge of frame 15 is bent 105 over to form an eye 16 for the reception of a pivot pin 17 and is recessed vertically, as at 18, at a plurality of points, corresponding in number to the number of key supporting devices desired. The frame 15 has at each 110

end ears 19 (Fig. 5), which, after the pin 17 has been inserted in eye 16 and through the eyes of the several key supporting devices, are bent at right angles to the body of frame 15 (Fig. 6) to prevent dislodgement of the pivot pin 17. Such construction dispenses with the necessity of heading over the ends of pin 17 and thereby facilitates the assembling operation.

10 The key supporting devices consist of snap hooks, which are represented generally by reference letter *h* in Fig. 1, and are clearly shown in detail in Fig. 3. These hooks are preferably made up of spring metal in the following manner. One end of the hook forming member is suitably adapted for pivotal connection with pin 17, as by bending it into an eye 20 and, from such eye, the body of the member, as 21, extends preferably in a substantially radial direction, as distinguished from tangentially, in order to allow the body portion to lie substantially flat against frame 15 as shown. The hook forming member is then bent backwardly upon itself and in generally converging relation with the body portion 21, as at 22, to form loops 23, which are of not unusual shape. The portion 22 extends into abutment with the portion 21, or substantially so, thereby forming the apex 24 of the loop, the walls of which loop are otherwise entirely unbroken as distinguished from the usual snap hook.

35 The free end of the hook forming member is bent outwardly beyond the apex 24, as at 25, and in diverging relation to the portion 21. This construction facilitates the insertion of a key in the loop 23, the entrance to which is, of course, by way of the 40 "break" in the apex 24 of the loop and between the abutting portions 21 and 22. There is, however, an added reason for the projections 25. They effectually prevent, as shown in Fig. 4, the possibility of a key, 45 as *h*, when turned back from its normal pendant position in the loop, from lying flatly against the body 21, or nearly so, or in such position that the key might readily be worked out of the loop through its apex 50 24. The illustrated arrangement causes the key to assume a decided inclination to the body portion 21, when thus positioned, and increases the resistance to its removal through the apex by requiring a greater 55 spread between the portions 21 and 22, which resistance is, in practical effect, sufficient to prevent accidental dislodgement of the key from the loop.

60 To still further guard against the accidental dislodgement of keys, more particularly thin keys, from the loops of the snap hooks, the latter may be made in the manner shown in Fig. 7. Such hook is formed generally as described but with this difference,— 65 viz—that the members 21 and 22 at their

abutting portions are caused to engage along a curved line, as at 27. Thus, the area of engagement between these members is materially increased and the liability of the key escaping correspondingly decreased. With 70 this construction, an appreciable gap between the members 21 and 22, due to permanent set in the material, may exist without affording a straight path for the escape of even thin keys.

75 The key case is used in substantially the same manner as set forth in my prior patent and it only remains to point out the utility of the special form of hook. The absence of breaks in the side walls of the loops is most 80 important for there can never be, even after extended use, any projections on the side walls upon which the keys may catch and cause eventual dislodgement in the manner described. The entrance to the loop, by 85 reason of its location at the apex, is entirely free of sharp corners or projections, which might cause trouble and furthermore the "break" in the loop is so remote from the usual position occupied by the key in the 90 loop, that the liability of dislodgement of the key is greatly lessened. The projection 24 likewise contributes toward prevention of dislodgement of the key from the loop, as heretofore described.

95 The invention has been disclosed herein, in an embodiment at present preferred, for illustrative purposes but the scope of the invention is defined by the appended claims rather than by the foregoing description. 100

What I claim is:—

1. A case for keys or the like, comprising a foldable supporting strip, and a plurality of snap hooks pivotally supported therefrom in longitudinally spaced relation for swinging movement in arc-like paths of substantially constant radius, each of said hooks comprising a body portion having one end bent to form a substantially circular eye for said pivotal connection and the other end 105 bent backwardly upon the body portion to form a key retaining hook and extending in substantially convergent relation to the body portion until in abutment therewith to close the loop and then bent away from the 110 body portion and terminating at a short distance therefrom.

2. A case for keys or the like, comprising a foldable supporting strip, a member secured to the latter and provided with a 120 pivotal support a plurality of hooks mounted on said support, said member being provided with openings in each of which one of said hooks is received, the walls of said openings limiting each hook in its longitudinal movement, each of said hooks comprising a main body portion bent at one end to form a substantially circular eye for engagement with said support and the other end of 125 which is bent backwardly upon the body 130

portion to form a key-receiving loop and converges toward and eventually into abutment with the body portion and then bent outwardly in divergent relation to the body portion and terminating at a short distance therefrom.

3. A case for keys or the like, comprising a foldable supporting strip, and a plurality of snap hooks spaced from each other, and pivotally supported therefrom and each adapted to removably support a key or the like, each of said hooks comprising a member adapted at one end for said pivotal connection and having a part extending away from such end and at a distance therefrom bent backwardly upon itself and extending in converging relation to said part until in abutment therewith, said backwardly bent portion being curved adjacent the apex of the loop and adapted to be received in a correspondingly curved portion in said part.

4. A case for keys or the like comprising a supporting strip, a member secured thereto having a plurality of tongues formed in one edge thereof and bent to provide aligned bearings, a rod mounted in said bearings and held against axial movement by lugs formed integral with said strip and bent over the ends of said rod, and a plurality of snap hooks each of which is pivotally supported from said rod between adjacent tongues, said hooks being each formed with a portion bent back upon itself to form a loop for the reception of a key and having the opposite end thereof bent closely about the rod to terminate in engagement with the body portion of said hook.

5. A case for keys or the like comprising a supporting strip, a member secured thereto having a plurality of tongues formed in one edge thereof and bent to provide aligned bearings, a rod mounted in said bearings and held against axial movement by lugs formed integral with said strip and bent over the ends of said rod, and a plurality of snap hooks each of which is supported from said rod, said hooks being each formed with a

portion bent back upon itself to form a loop for the reception of a key.

6. A case for keys and the like, comprising, a foldable supporting strip, a member secured thereto and affording a pivotal support, and a plurality of snap hooks pivotally supported from the latter in longitudinally spaced relation and for swinging movement into and out of the case in arc-like paths of substantially constant radius, each of said hooks comprising a member having one end so engaged with said support as to permit swinging movement and restrain radial movement of the hook relative thereto and having a part extending away from such end and at a distance therefrom bent backwardly upon itself and extending in substantially converging relation to said part until in abutment therewith, said backwardly bent portion being then bent away from said part and terminating at a short distance therefrom.

7. A case for keys or the like, comprising, a flexible supporting strip, a member secured thereto and provided with a plurality of slots, a plurality of hooks having a pivotal connection with said member and arranged in longitudinally spaced relation, said hooks extending through said slots and limited in their longitudinal movement by engagement with the walls thereof and free for swinging movement into and out of the case along arc-like paths of substantially constant radius; each of said hooks comprising a one-piece member having a part at one end adapted for said pivotal connection and to permit said swinging movement, a part extending away from such end and at a distance therefrom bent backwardly upon itself to form a key retaining loop, said backwardly bent portion eventually abutting the second named part near the other end of said second-named member to close said loop.

In testimony whereof I have affixed my signature.

WARNER R. BUXTON.
